UNITED STATES PATENT OFFICE.

WILLIAM H. TAYLOR, OF DES MOINES, IOWA.

WINDOW-FRAME AND CHUTE STRUCTURE.

1,390,178.

Specification of Letters Patent. Patented Sept. 6, 1921.

Application filed April 9, 1920. Serial No. 372,698.

To all whom it may concern:

Be it known that I, WILLIAM H. TAYLOR, a citizen of the United States, and resident of Des Moines, in the county of Polk and 5 State of Iowa, have invented a certain new and useful Window-Frame and Chute Structure, of which the following is a specification.

The object of my invention is to provide a 10 window frame and chute structure of simple and durable construction, peculiarly adapted to be mounted in a suitable opening and to be used for putting coal or the like through such opening.

15 A further object is to provide in such a structure a novel means for supporting a chute in position for use, or in position received within the building.

Still a further object is to provide in such 20 a structure, a protecting shield which will be out of the way when not in use, and will protect the wall above the frame while the chute is in use.

With these and other objects in view, my 25 invention consists in the construction, arrangement and combination of the various parts of the device, whereby the objects contemplated are attained, as hereinafter more fully set forth, pointed out in my claims, and 30 illustrated in the accompanying drawings, in which:

Figure 1 shows a perspective view of a portion of a wall having an opening provided with a frame and chute structure embodying my invention.

Fig. 2 shows a front elevation of the same with the parts in different positions, and with a window installed in the frame.

Fig. 3 shows a detail sectional view of 40 the frame and chute structure, taken on the line 3—3 of Fig. 1.

Fig. 4 shows a detail view of part of the structure.

Fig. 5 shows another detail view, illustrating the construction and arrangement of the shield supporting arm.

Fig. 6 shows a detail sectional view, taken on the line 6—6 of Fig. 2.

Fig. 7 shows a similar view with the window and the chute member removed and with the shield in another position.

Fig. 8 is a detail top view of one corner of the chute structure; and

Fig. 9 shows a detail sectional view, taken 55 on the line 9—9 of Fig. 8.

In the accompanying drawings I have used the reference numeral 10 to indicate generally a section of a wall having a window opening therein.

My improved frame comprises a frame 60 made of angle iron in the form of a rectangle, as illustrated, for instance, in Figs. 1 and 2, and preferably made of a single piece of angle iron cut and bent at the corners and having outer vertical flanges and 65 inwardly extending horizontal flanges. The frame is indicated generally by the reference character A, and the outer flanges are indicated by the numeral 11, and the horizontal flanges by the numeral 12. The corners of 70 the frame are reinforced by corner pieces 13.

After the frame has been inserted in the opening, angles 14, such as that shown in Fig. 3, may be fastened to the upper flange 12 and arranged with an inner, upwardly 75 extending flange 14^a, which engages the inner surface of the wall.

Secured to the inner surface of each side flange 12, near the upper part thereof but spaced below the upper flange 12, is a shelf 80 or the like 15, preferably made of a piece of angle iron having at its forward end an upwardly extending flange 16 and at its rear end a shorter upwardly extending flange 17. The two shelf members 15 are arranged opposite each other.

I provide for coacting with the shelf members 15, which extend from the rear of the side flanges 12 to points terminating short of the front edges thereof, a chute 90 comprising the substantially triangular end members 18 and a bottom member 19. The upper forward edge of the bottom member 19 is preferably reinforced with an angle iron 20, as shown in Fig. 1, but the angle 95 iron may be dispensed with if desired.

Secured to the inner surfaces of the end chute members 18, at the upper corners thereof, are angle iron brackets 21. Secured to the horizontal flanges 21^a of the 100 brackets 21 is an angle iron 22 which extends across the chute and has ends which project beyond the end walls 18 of the chute, as illustrated at 22^a in Fig. 8.

In assembling the chute on the window 105 frame, the chute is grasped and the ends 22^a are lifted over the flanges 17 in the space between the upper ends of said flanges and the upper frame flange 12, and said ends 22^a are then allowed to rest on the 110

shelves 15, as illustrated, for instance, in Fig. 6.

Arranged just outside the shelves 15, within the main frame at the sides of the main frame, are angle iron frame members 28, connected at the top by a cross bar 29 and adapted to serve as a jam or the like for a window 30. On the upper surface of the lower flange 12, just rearwardly of the frame members 28, is an upwardly and forwardly inclined catch or stop device 31.

When the window 30 is installed, and the chute device is not in use, it may be permitted to hang, as shown in Fig. 6. When it is desired to use the chute for putting coal through the frame, the window is removed. It may be noted that the side frame flanges 12 are provided with suitable openings 32 to receive ordinary window stops 33 for holding the window in position.

After the window has been removed, the chute is slid on the shelves 15 to the forward ends of said shelves, and is then swung forwardly and upwardly to the position shown in Figs. 1 and 3 and until the bottom of the chute clears the stop 31 and projects below it, as illustrated, for instance, in Fig. 3. The chute will then be held in position for use.

I preferably provide in connection with the frame and chute structure just described, a shield. The shield includes arms 34, each having at one end an off-set portion 35 pivoted to one of the upright end flanges 12 at a point spaced below the shelf 15 and near the angle frame 28, as shown in Fig. 6. The extreme end of each arm 34 adjacent to the pivot 36 thereof, is bent so as to stand spaced from the flange 12 at a distance about equal to the thickness of the flange of the frame member 28 which is secured to the flange 12, as illustrated, for instance, in Fig. 5 at 34. At the other end of each arm 34 is an inclined arm member 37. The inclined arm members 37 are connected by a shield 38. One the arms 34 are buttons 39.

Ordinarily the shield hangs in the position shown in Fig. 6, but when the chute is used the shield is swung upwardly and forwardly to its position shown in Fig. 3, where it stands in front of and projects above the upper flange 11 of the main frame, for protecting the wall 10 above the frame. The arms 34 are somewhat resilient, and when the shield is in its operative position shown in Fig. 3, the buttons 39 stand just rearwardly of the forwardly projecting flanges of the members 28, as shown, for instance, in Figs. 4 and 5, for holding the shield in its raised position.

When desired the chute may be removed by lifting the ends of the angle iron member 22 over the flanges 17, and after the chute has been removed the shield may be moved out of the way for permitting free ventilation or free passage through the window by raising the shield rearwardly and upwardly to its position shown in Fig. 7. The ends 34^a of the arms 34 are so arranged that when the shield is raised to its position shown in Fig. 7, said ends will frictionally engage the inwardly projecting flanges of the members 28 for holding the shield in its raised position.

It will be seen that the frame may be used with or without the shield and chute and that the frame and shield may be used without the chute where desired. The shield and chute are both within the building, back of the window 30, and protected from the weather when not in use.

Some changes may be made in the construction and arrangement of the parts of my device, without departing from the real spirit and purpose of my invention, and it is my intention to cover by my claims any modified forms of structure or use of mechanical equivalents which may be reasonably included within their scope.

I claim as my invention:

1. In a device of the class described, the combination of a frame having rearwardly extending side flanges, a chute comprising side members and a bottom member, means for slidably and pivotally supporting the upper ends of said side members on said flanges, said means being adapted to permit the raising of said chute, and means at the bottom of said frame for engaging said chute and holding it when in position for use.

2. In a device of the class described, the combination of a frame having rearwardly extending side flanges, a chute comprising side members and a bottom member, means for slidably and pivotally supporting the upper ends of said side members on said flanges, said means being adapted to permit the raising and removal of said chute, and means at the bottom of said frame for engaging said chute and holding it when in position for use.

3. In a device of the class described, the combination of a frame having inwardly extending flanges adapted to be received in an opening, having near its forward portion frame members against which a window may be placed, means rearwardly of said last frame members for slidably and pivotally supporting a chute, a chute having end members and a bottom member, and having means projecting beyond said end members for coacting with said last described means, and a stop means for the bottom of the chute for holding it in position for use, said stop means being located rearwardly of said window engaging means, the parts being so arranged that when the window is removed the chute may be shoved forwardly and held adjacent for use, and

being so arranged that the chute may be slid rearwardly and hung in position where it will not interfere with the window.

4. In a device of the class described, the combination of a frame having rearwardly extending flanges at its sides, with frame devices at its sides spaced from its forward portion, having inwardly extending flanges adapted to engage a window, a shield com-

prising arms having off-set portions pivoted to said side flanges, a shield mounted on said arms, said arms being resilient, and engaging members on said arms for coacting with said last described flanges for holding the shield in raised position. 10
